UNITED STATES PATENT OFFICE.

JAMES A. LOYSTER, OF CAZENOVIA, NEW YORK.

CLOSURE FOR BOTTLES AND JARS.

1,340,783.

Specification of Letters Patent. Patented May 18, 1920.

Application filed December 9, 1918. Serial No. 805,600.

To all whom it may concern:

Be it known that I, JAMES A. LOYSTER, a citizen of the United States, and resident of Cazenovia, Madison county, State of New York, have invented certain new and useful Improvements in Closures for Bottles and Jars, of which the following is a specification.

The present invention comprises a tab or handle, or pulling device, in combination with a disk bottle closure, for withdrawing the disk from the bottle or jar. I have produced a tab which is very thin and which normally lies flat upon the disk, thus permitting the disks to be stacked closely for shipment and storage. I have further provided means whereby the tab may be easily grasped and securely held by the fingers, and attaching means which insure it from pulling away from the disk. My invention further comprises a structure which is very readily attached to the disk without special means for perforating the latter.

The invention will be described in connection with the accompanying drawing, in which,

Figure 1 is a plan view of a disk closure embodying my invention;

Fig. 2 is a section on the line 2—2 of Fig. 1;

Fig. 3 is a side view of the pulling tab;

Fig. 4 is a bottom plan view of the same;

Fig. 5 is a section on the line 5—5 of Fig. 4;

Fig. 6 is a section on the line 6—6 of Fig. 4;

Fig. 7 is a plan view of a modified form of the invention;

Fig. 8 is a section on the line 8—8 of Fig. 7;

Fig. 9 is a partial plan view of another form;

Fig. 10 is a section on the line 10—10 of Fig. 9, and,

Fig. 11 is a sectional view of a container showing a number of the disk closures stacked therein.

Referring to Figs. 1 to 6 inclusive, A indicates the disk of paraffined cardboard or other suitable material and B indicates the pulling tab. The tab is preferably made of thin, tough sheet metal, such as thin sheet iron. It is connected to the disk preferably

by two prongs c, c, punched from the tab in the same direction and near one end thereof. 55 In constructing these tabs, as shown in the drawing, substantially circular pieces are punched from the strip and bent downward nearly at right angles, being somewhat elongated and concavely curved in the punching 60 operation. This operation slightly draws the metal and renders it more rigid and the curvature in cross section adds to the rigidity. I furthermore so shape and operate the dies as to make the extreme ends of the 65 prongs thin, giving them edges or points which may be readily driven through the paper or material of the disk. Thus in the preferred form of the invention the prongs c, c are punched from substantially circular 70 openings 12 and are curved in cross section throughout their middle portions 13, and are bent backward and slightly sharp at their points 14.

The tab is arranged radially on the disk 75 and the prongs, preferably two in number, are forced through the disk and turned backward and clenched, as shown at 15 in Fig. 2. The tab normally lies perfectly flat upon the disk, reaching to or slightly beyond the center thereof, the end overlapping a depression D. This depression may be made by compressing the middle portion of the disk, or cutting away a portion, or in any other suitable manner. It is preferably 80 substantially semicircular, being bounded by a curved line 16 surrounding the end of the tab and a straight line 17 crossing the tab near its end. This permits the finger nail to be inserted under the end of the tab 85 for the purpose of raising the same. When the tab is raised, as indicated in dotted lines in Fig. 2, it is grasped by the thumb and finger and the stopper may be disengaged from the bottle by pulling it. In order that the tab may be held firmly, one or more holes 18 are punched in its free end. It will readily be observed that the thumb and finger will sink into these holes and prevent the tab slipping away when grasped firmly. 100

In Figs. 7 and 8 I have shown substantially the same structure as in Figs. 1 to 6, with the exception that the tab is secured to the disk by one long prong c' instead of two shorter ones. This prong is oblong in 105 shape, being punched from the oblong open-

ing 19. It possesses the same characteristics of curvature, stiffness and sharpness that are possessed by the prongs c , c .

The form of my invention shown in Figs. 5 9 and 10 comprises a thin metal strip B^2 connected to the disk A^2 by two prongs c^2 , c^2 , these prongs being preferably the same in structure as the prongs c , previously described. In this case the tab extends diametrically across the disk being connected to the disk at its margins and free at the middle so that it may be raised by the thumb and finger into the position shown in dotted lines, Fig. 10, for pulling the disk from a 15 bottle. In order that the tab may be grasped I form two semi-circular depressions D^2 in the middle of the disk, with a narrow separation between them.

It will be noted that in the various forms 20 of my invention the outer ends of the prongs are bent toward the center of the disk and hence there is no tendency to detach them from the disk when pulling the tab. It will also be noted that they can be passed 25 through the disk and clenched without leaving any opening or vent therein and that the tab does not extend to the periphery of the disk and hence the latter can be perfectly circular and have an air-tight fit with 30 a properly shaped bottle neck.

A very important feature of my invention resides in the shape of the prongs which are rigid and may be driven through a disk of any suitable material without bending. This 35 shape is preferably a circular segment in cross section, although the required stiffness might be obtained by a different cross section, differing, however, from a flat form. It will be evident that a perfectly flat prong 40 would not be so strong and might bend one way or the other when being driven unless special devices for supporting it were used. Furthermore by elongating it during the 45 punching operation, by a swaging action, I impart to it additional stiffness or "temper" which aids greatly in strengthening it. I believe I am the first to so shape the prong or prongs of a tin or other thin sheet metal tab for a bottle cap that they may be driven 50 through the usual paper board caps without lateral support. It will be understood 55 that the length of the prong or prongs may vary and should be adapted to the particular thickness of the material used for the caps.

Another important feature of my invention is the use of two prongs on the tab, passing through the margin of the disk, and both bent toward the middle of the disk. 60 This makes a very secure attaching means, each prong tending to prevent the other from becoming accidentally detached. By bending the prongs toward the center of the disk, it will be seen that they tend to take 65 an even stronger grip of the disk when the

tab is pulled, as the pull is usually slightly away from the margin of the disk and not entirely at right angles to the disk. Furthermore, should the material of the disk yield and the first prong pull out the tab 70 will still be securely held by the second prong.

By the use of my method of stiffening the prongs for driving, the metal of the tab may be very thin and the caps will therefore lie 75 very close together when stacked. This is very important as, from sanitary and commercial standpoints, it is important to be able to pack the caps closely in tubes or boxes, as illustrated in Fig. 11.

The sheet metal tab is preferably oblong and narrow so as to obscure as little as possible the printed or advertising matter which is usually put on caps of this character. It will be noted that the attaching prong nearest the end is not formed by bending the end of the tab, but by punching out a part from the body of the tab, leaving the end nearest the margin of the cap intact. This makes a much more reliable securing means than 90 would be the case were the end of the tab formed into a prong or tang and driven through the cap, as in such case the tab would tend to turn bodily about the point of connection instead of bending at that 95 point.

In order to facilitate the bending of the tab at the most desirable place, and to make it easier to bend, I preferably make an additional perforation 20 close to the prong 100 which is nearest to the center of the disk. In such case the tab will bend on a transverse line substantially through the center of the perforation 20, as indicated in dotted lines in Fig. 2. This result could be obtained by weakening the tab at this point by equivalent means, such as notching it at the sides, or making the perforation of a different shape. It is preferred, however, to punch a round hole as shown, as this is 110 easier made from a mechanical standpoint, and leaves the outer edge of the tab smooth.

Having described my invention what I claim and desire to secure by Letters Patent is:

1. A sheet metal tab for a bottle or jar closure having a prong punched from the sheet and extending at an angle thereto, the said prong being bent transversely to stiffen it and said tab being weakened near the 120 prong to facilitate bending.

2. A sheet metal tab for a bottle or jar closure having a prong punched from the tab near one end and extending at an angle thereto, the said prong being curved transversely to stiffen it, said tab having a hole near the other end to form a grip and being weakened between said prong and grip to facilitate bending.

3. A sheet metal tab for a bottle or jar 130

closure having a prong punched from the sheet and extending at an angle thereto, the said prong being near one end of the tab and concave toward the nearer end of the tab.

4. A sheet metal tab for a bottle or jar closure comprising a thin metal strip having a prong punched from the body thereof near one end of the strip, the said prong being curved transversely and connected to the strip at the inner edge of the opening from which it is punched, the end of the strip adjacent the prong being undisturbed.

5. A sheet metal tab for a bottle or jar closure having a substantially circular portion punched from its body near one end thereof, said portion being formed into an elongated prong extending substantially at right angles to the tab and bent in cross section and the material of said prong being stiffer than the material of the tab.

6. A sheet metal tab for a bottle or jar closure comprising an elongated strip of thin metal having two prongs punched therefrom near one end and in line with the axis thereof, said prongs being bent in cross section and connected with the strip at the inner ends of the openings from which they are struck, for the purpose set forth.

7. A sheet metal tab for a bottle or jar closure comprising an elongated piece of metal having two centrally located prongs punched therefrom near one end thereof, said prongs being curved in cross section, the concave sides of the prongs facing the nearer end of the tab.

8. The combination with a disk bottle or jar closure of a sheet metal tab arranged to lie flat upon the upper surface of the disk and having its outer end connected to

the margin of the disk, the said disk being provided with a depression in its upper surface over which the free end of the tab lies, whereby the under surface of the tab may be reached to raise the tab, the said depression being substantially semicircular in outline and the tab being arranged to cross the straight boundary portion thereof and to terminate near the middle of the depression. 45

9. A closure disk having a length of flat 50 wire arranged flat face down on the top face of the disk, the outer end portion of the wire forming a base secured on said top face, said wire extending inwardly on the disk from said base to form a free handle end, 55 a portion of said wire being weakened, said free end adapted to be bent to upright handle position on said weakened portion to exert upward disk extracting pull on said base, means being provided whereby said base is tightly and permanently gripped to and against rocking on said disk.

10. A closure disk having a straight length of flat wire arranged flat face down on the top face of the disk, the outer end portion 65 of the wire constituting a base, areas of said wire extending through the disk to permanently and tightly secure said base down on the top face of the disk, said wire extending inwardly of the disk from said base 70 to form a free handle end adapted to be bent to upright handle position to exert direct upward disk extracting pull on said base.

In testimony whereof I affix my signature 75
in presence of two witnesses.
